UNITED STATES PATENT OFFICE

2,159,293

DOLL

Edward G. Schaeffer, Brooklyn, N. Y., assignor
to American Character Doll Co., Inc., New
York, N. Y., a corporation of New York

Application July 24, 1936, Serial No. 92,333

9 Claims. (Cl. 46—169)

This invention relates to dolls and more particularly to a doll structure having eyeballs pivotally mounted therein with automatic mechanism for moving the eyeballs into closed, sleeping position and into open, waking position.

In accordance with this invention, an eyeball assembly is provided which includes one or more eyeballs pivotally mounted for movement into open and closed position having associated there-
10 with eyeball-operating mechanism assembled as a complete unit before it is inserted into the doll head. The unit may be suitably clipped, fixed, or otherwise attached within the doll head, or, if desired, the unit may be incorporated with the
15 doll head mold and then molded into place as the doll head itself is molded or formed.

In one form of my invention the eyeballs are fixed to a suitable rock shaft which is pivotally supported in a bracket fixed, secured, clamped, or otherwise secured within the doll head. A suitable weighted pendulum is fixed to the rock shaft so that when the pendulum is acted upon by gravity, it will move the eyes into closed or open position upon predetermined rocking or lifting movement of the doll body. A guide rack for the pendulum is integrally formed with or secured to the bracket. The guide rack is provided with an elongated slot through which the pendulum member extends. The rack is pro-
20 vided with a series of barbs which successively interrupt the movement of the pendulum when it swings the eyeballs to closing position so as to require sidewise rocking of the doll head to successively advance the pendulum into eye-closing
25 position. This operation takes place as the doll is rocked in its crib or in the arms of its child-mother. When the doll is raised into vertical or aroused position, the pendulum will return to its eye-opened position without obstruction from the
30 barbs.

The eyeball and eyeball-operating unit can be inexpensively made and assembled with a minimum of operations, and largely by unskilled labor, and can be advantageously assembled in doll heads designed to retail at comparatively low cost. The movement of the eyeballs is such as to closely simulate the eyeball movement in the human baby when it is rocked to sleep and when
45 picked up and aroused. The child-mother obtains great happiness and delight from the doll as herein constructed, since its eye performance, to which the child is immediately attracted, is very similar to that of a natural baby.

50 An object of this invention is to provide a

sleeping doll having eyeballs which can be closed by a solicitous rocking movement of the doll.

Another object of this invention is to provide an improved eyeball mounting and eyeball-operating mechanism which may be assembled as a 5 complete unit and the unit thereafter inserted, attached, or otherwise applied to the doll head.

Still another object of this invention is to provide an improved eyeball unit having eyeball-mounting and operating mechanism associated 10 therewith which can be produced at low cost, which is substantially foolproof and positive in operation, and which is sturdy and strong in construction.

Other objects of this invention will become 15 apparent as the disclosure proceeds.

Various other features and advantages of the invention will be apparent from the following particular description and from an inspection of the accompanying drawing.

Although the novel features which are believed to be characteristic of this invention will be particularly pointed out in the claims appended hereto, the invention itself, as to its objects and advantages, and the manner in which it may be carried out, may be better understood by referring to the following description taken in connection with the accompanying drawing forming a part thereof, in which:

Fig. 1 is a vertical cross-sectional view through 30 a portion of a doll head, showing particularly the eyeballs, the mounting therefor, and the mechanism for manipulating the eyeballs to closed and open position, this view being taken on line 1—1 of Fig. 2;

Fig. 2 is an elevational view looking into the front section of the doll head and showing a rear elevational view of the doll's eyeballs, the mounting therefor, and the eyeball-manipulating mechanism, this view being taken on line 2—2 of 40 Fig. 1;

Fig. 3 is an enlarged perspective view of the eyeball mounting and the eyeball-manipulating mechanism, one of the eyeballs being removed to show the structure to the rear of same;

Fig. 4 is an enlarged plan view of the eyeballs, the mounting therefor, and operating mechanism, this view being taken along line 4—4 of Fig. 2 looking in the direction of the arrows; and

Fig. 5 is a front elevational view looking directly at the eyeballs, this view showing the eyeball mounting and the operating mechanism therefor.

Similar reference characters refer to similar 55

parts throughout the several views of the drawing and specification.

Referring more particularly to Figs. 1 to 5 inclusive, there is shown for purposes of illustration the front half 1 of a doll head, having facial features 2. The doll head may be made from porcelain, phenol resins, vulcanized rubber, or other earthy, metallic, fibrous, resinous, or moldable materials well known in the art. The eyeballs 5, the mounting therefor, and the eyeball-operating mechanism, are assembled as a complete unit and then inserted within the doll head. Where the doll head is molded, stamped, or otherwise formed, the eyeballs, eyeball mounting and eyeball-operating mechanism may be quickly inserted through the opening 3 in the neck portion of the doll and affixed in position. If desired, the unit may be molded into position as the doll head is formed or cast.

The eyeballs 5 are colored or otherwise formed so that the pupil 6a, the iris 6b, and the sclerotic coat 6c will have the appearance and likeness to the human eye. Eyelashes 7 comprising a plurality of parallel-arranged hairs or fibers are cemented or otherwise secured to the eyeball over the iris. The upper portion 6d of the eyeball 5 is suitably coated or decorated to give the appearance of the human eyelid when closed. The eyeballs 5 are fixed to the respective ends of a shaft 8 which is suitably mounted on the flange portions 11 of a supporting bracket 10. Flange portions 14 extending from the bracket 10 are provided with inwardly extending prongs 15 which are adapted to be pressed or clamped into gripping engagement with an inwardly extending projection 16 molded or otherwise secured to the interior of the skull 1. The bracket 10 may be quickly secured in position by means of a suitable clamping tool so as to rigidly support the eyeballs 5 in proper position within the doll head, so that the opening 5a in the facial portion 2 provides a realistic frame for the eyeball.

The shaft 8 supporting the eyeballs 5 preferably extends through elongated slots 12 in the flange portions 11, the shaft 8 being retained therein by a bent over nose portion 13 which substantially closes the outer ends of the slots. The nose portion 13 may be bent over after the shaft 8 has been inserted into the slots 12. The shaft 8 is frictionally retained in the fixed position by means of a suitable spring element 17 having one end 18 thereof fixed to the bracket 10 and the other end 19 frictionally engaging the shaft 8 so as to resiliently press shaft 8 against the nose portion 13. The frictional grip of the spring element 17 should be such as to normally retain the eyeballs in fixed position until the eyeball-moving mechanism now to be described is brought into play.

The eyeball-motivating mechanism may comprise a bar 22 having a weight 23, such as a piece of lead, secured to the one end thereof. The other end of the bar is connected to the shaft 8 by means of a suitable loop 24 which extends through an opening or hole in the shaft 8. Thus it is seen that the bar 22 and the weight 23 which it supports is normally free to swing as a pendulum in a plane substantially perpendicular to the shaft 8.

The swinging movement of the pendulum, comprising the bar 22 and associated weight 23, is definitely limited by an elongated slot 21 cut into a guide rack 20 through which the bar 22 extends. The guide rack 20 may be provided with elements 26 clamped to a projection 27 extending from the lower end of the bracket 10. It is understood,

however, that the guide rack 20 may be formed integrally with the bracket 10, if desired. The slot 21 extends in a direction generally transverse to the shaft 8, as clearly shown in Fig. 3, and the movement of the eyeballs 5 from open to closed position and vice versa is measured by the length of the slot 21.

It will be noted that the slot 21 is provided with a plurality of inwardly extending barbs 30 or projections which are designed to cause the bar 22 to partake of a zigzag path as it passes from one end 21a of the slot to the other end 21b of the slot. This zigzag movement of the bar 22 can be effected, when the eyeball-operating mechanism is mounted within the head of the doll, by giving the bar 22 and its associated weight 23 a pendulum swinging movement. This pendulum swinging movement is effected by rocking the doll sidewise back and forth as it lies in its cradle or in the arms of its child-mother. The eyeballs are thus given a gradual closing movement during which the eyelashes 7 gradually drop downward, concealing the pupil 6a and iris 6b from view, so that the eyelid portion 6d only is visible through the opening 5a in the facial portion 2. It will be noted that the barbs are so shaped as to provide seats on their upper faces and cam surfaces on their lower faces.

The operation of the eyeball-closing mechanism is as follows: When the doll head and associated doll body is given a sidewise rocking movement such as is customary in putting to sleep the human baby, the bar 22, motivated by gravity acting on the weight 23, will swing off from the seat 31 which it occupies when the doll's eyes are in open position, and will move onto the opposite seat 32. A rocking movement in the opposite direction will cause the bar 22, motivated by the action of gravity to slip off from its seat 32 and onto the opposite seat 33, which is one stage closer to the eye-closed end 21b of the slot 21. Continued to-and-fro rocking movement of the doll will cause the bar 22, motivated by gravity acting upon its weight 23, to drop successively onto the seat 34, the seat 35, the seat 36, the seat 37, and so on until the pupil and iris, 6a and 6b respectively, are no longer visible and only the eyelid portion 6d is visible through the eye opening 5a. The doll's eyeballs in this position closely simulate the closed lids of a sleeping baby, and the eyeballs are supported in closed, sleeping position by the seat 40 at the end of the slot 21. It is thus seen that the eyelashes 7 and eyelids 6d are brought into closing position by gradual stages, which closely simulates the gradual closing of a baby's eyes as sleep approaches. When the doll is to be aroused from its slumber all that is necessary is to lift the doll into upright position or partially upright position, which will cause the weight 23 attached to the bar 22 to leave its seat 40 and move forwardly to the other end 21a of the slot. The inwardly projecting barbs do not interfere with this movement inasmuch as they are provided with lower cam surfaces 41, which permit the bar 22 to move forwardly substantially unobstructed. It is understood that the slot 21 may be as long as is necessary to effect complete closing and opening of the doll's eyes and as many inwardly projecting barbs 30 may be provided as desired to effect closing of the doll's eyes by successive stages or intervals. The more barbs there are, the greater number of sidewise rocking movements will be required to completely close the eyes, and it is evident that if a large number of closely spaced barbs are provided the closing can 75

be effectuated without substantially visible jerking movement, so that the closing of the eyes appears to the child-mother entirely natural and similar to the gradual closing of a natural baby's eyes.

Since the eyeball mounting and operating mechanism is all formed as an integral unit before insertion into the doll head, the same can be inexpensively manufactured from stamped parts and quickly and easily assembled. The entire eyeball-supporting and manipulating unit may be assembled within the doll head and suitably secured in position by clamps or other securing means at a high rate of speed, thus assuring a low cost of manufacture and positive operation of the parts. Heretofore eyeball-operating mechanism comprising several parts has been separately assembled in the doll head, and doll heads as thus constructed are expensive since much time and considerable skill are required to assemble the parts in the doll head in the proper relationship.

The eyeball mounting and operating mechanism herein described can be used with many different varieties of dolls. Heretofore, so-called sleeping dolls have been expensive due to the fact that the eye-operating mechanism has been unduly complicated and difficult to assemble in the doll head. The eyeball-operating mechanism herein disclosed is assembled with the eyeball as a complete, integral functioning unit, thus avoiding the difficulty of assembling the parts under cramped conditions within the doll head. The complete eyeball-operating unit may be inserted into the doll head through the neck opening, or if the head is assembled in two parts the eyeball-operating unit can be inserted in the head prior to the application of the back portion of the head to the facial portion, or if desired the unit may be placed in a suitable head-shaping mold and the head molded around the unit. In such cases the molding material would be made of disintegratable material so that it can be removed after the head has been cast.

Since the eyeball, eyeball mounting and operating mechanism are first formed as an assembled unit prior to the insertion thereof into the doll head, the same can be made and assembled on a mass production basis substantially entirely by automatic machinery and with a minimum amount of labor. The unit can thus be made at very low cost and can be embodied as a feature in doll bodies marketable at a price considerably below the price of dolls heretofore made having eyes which are rocked to sleep. The unit is sturdy and strong in construction, positive in operation, and the functional parts are so correlated as to operate efficiently and effectively. The moving parts are so supported that jars given to the doll body or doll head will not displace or disarrange the parts. The eyeball-operating mechanism can be associated with doll bodies of innumerable shapes and forms and made from all the various materials commonly used in the art.

While certain novel features of the invention have been disclosed and are pointed out in the annexed claims, it will be understood that various modifications, omissions, substitutions and changes may be made by those skilled in the art without departing from the spirit of the invention.

What is claimed is:

1. A sleeping doll including, a doll head having a facial portion and an eye opening in said facial portion, mounting means positioned above said eye opening, and providing a single point of suspension and an integrally assembled eyeball unit

fixedly suspended from said mounting means, said unit including a pair of eyeballs, means pivotally mounting said eyeballs, and mechanism forming a part of said unit for closing said eyes by stages when the doll is rocked.

2. A sleeping doll including in combination, a doll head, and an integrally assembled eyeball unit mounted within said doll head, said unit including a bracket having clamping jaws gripping a portion of the doll head, eyeballs pivotally mounted on said bracket, means operably connected to said eyeballs designed to pivot said eyeballs into open and closed position, a guide rack associated with said pivot means fixed to and supported by said bracket, said guide rack including a plate member having an elongated slot therein, barbs projecting inwardly into said slot so as to cause said pivot means to describe a zigzag path as it moves along said slot, and means resisting pivotal movement of said eyeballs which may be overcome by gravity operating upon a weighted element associated with said pivot means.

3. A sleeping doll including, a doll head having a facial portion, an eye opening in said facial portion, and a projection integrally formed with said doll head positioned above said eye opening, and an integrally assembled eyeball unit fixedly suspended from said projection, said unit including a pair of eyeballs, a bracket pivotally mounting said eyeballs, and mechanism forming a part of said unit for closing said eyes by stages when the doll is rocked, said bracket having spaced elements adapted to be pressed into gripping engagement with said projection to suspend said eyeball unit in fixed position within the doll head.

4. A sleeping doll including in combination, a doll head, and an integrally assembled eyeball unit fixedly suspended from a single point within said doll head, said unit including a bracket fixed within the doll head, eyeballs pivotally mounted on said bracket, a pendulum operatively connected to said eyeballs designed to pivot said eyeballs into open and closed position, and a guide rack associated with said pendulum fixed to and supported by said bracket, said pendulum including a stem portion extending through said guide rack, a weight fixed to the end of said stem portion exterior to said guide rack, and resilient means resisting pivotal movement of said eyeballs which may be overcome by the swinging movement of said pendulum.

5. In combination with a doll head having a facial portion, eye openings in said facial portion, mounting means in said head positioned between said eye openings, and a unitary integrally assembled eyeball and eyeball-operating mechanism within the doll head, said mechanism including a bracket stamped from a single piece of sheet metal having spaced prongs adapted to be laterally pressed into gripping engagement with said mounting means to retain said bracket in fixed suspended position within the doll head, an eyeball positioned adjacent each of said eye openings, means pivotally mounting said eyeballs on said bracket, means for pivoting said eyeballs, and means fixedly secured to said bracket for controlling in successive stages the pivoting movement of said eyeballs into closed sleeping position.

6. A sleeping doll including in combination, a doll head having a facial portion and eye openings in said facial portion, mounting means positioned between and above said eye openings, and an integrally assembled eyeball unit fixedly suspended from said mounting means, said unit including

- a bracket having spaced prongs adapted to be laterally pressed into gripping engagement with said mounting means to retain said bracket in fixed suspended position within the doll head, eyeballs pivotally mounted on said bracket, a pendulum operably connected to said eyeballs designed to pivot said eyeballs into open and closed position, and a guide rack associated with said pendulum fixed to and supported by said bracket.
10. 7. A sleeping doll including in combination, a doll head having a facial portion and eye openings in said facial portion, mounting means positioned between and above said eye openings, and an integrally assembled eyeball unit fixedly suspended from said mounting means, said unit including a bracket fixedly suspended from said mounting means, said bracket having clamping jaws gripping said mounting means, eyeballs pivotally mounted on said bracket, a pendulum operably connected to said eyeballs designed to pivot said eyeballs into open and closed position, a guide rack associated with said pendulum fixed to and supported by said bracket, and means resisting pivotal movement of said eyeballs which may be overcome by the swinging movement of said pendulum.
15. 8. A sleeping doll including in combination, a doll head having a facial portion and an eye open-
- ing in said facial portion, mounting means positioned above said eye opening and formed as a portion of the doll head, and an integrally assembled eyeball unit fixedly suspended from said mounting means, said unit including a bracket fixedly suspended from said mounting means, a shaft pivotally supported by said bracket, an eyeball fixed to said shaft, a pendulum operably connected to said shaft designed to pivot the shaft and said eyeball into open and closed position, and a guide rack associated with said pendulum fixed to and supported by said bracket.
9. A sleeping doll including in combination, a doll head, and an integrally assembled eyeball unit fixedly suspended from a single point within said doll head, said unit including a bracket having clamping jaws gripping a portion of the doll head, a rock shaft pivotally mounted on said bracket, a pair of eyeballs fixed to said rock shaft, a pendulum connected to said rock shaft and designed to pivot the eyeballs into open and closed position, a guide rack associated with said pendulum fixed to and supported by said bracket, and a resilient element integrally formed with said bracket for resisting pivotal movement of said eyeballs which may be overcome by the swinging movement of said pendulum.

EDWARD G. SCHAEFFER.
